Inventor,

Raymond T. Bell,

By *John J. Gochman Jr.*

UNITED STATES PATENT OFFICE.

RAYMOND T. BELL, OF CHICAGO, ILLINOIS.

PENCIL.

Application filed February 13, 1922. Serial No. 536,255.

To all whom it may concern:-

Be it known that I, RAYMOND T. BELL, a citizen of the United States, residing at Chicago, in the county of Cook and State of Illinois, have invented certain new and useful Improvements in Pencils, of which the following is a specification.

This invention relates to improvements in pencils of the type in which the lead or crayon is adapted to be fed from the holder or barrel as the lead is consumed, and one of the objects of the invention is to provide an improved pencil of this character having means for automatically feeding the lead by a step by step movement and means whereby the feeding movement may be controlled at will.

To the attainment of these ends and the accomplishment of other new and useful objects as will appear, the invention consists in the features of novelty in substantially the construction, combination and arrangement of the several parts hereinafter more fully described and claimed and shown in the accompanying drawing illustrating this invention and in which—

Figure 1 is a longitudinal sectional view of a pencil constructed in accordance with the principles of this invention, showing the parts in one position with the lead or crayon clamped in position for use.

Figure 2 is a view similar to Figure 1, showing the parts in another position and with the lead unclamped or released to permit a feeding movement.

Figure 3 is an enlarged detail end view of the cap showing the portion for controlling the operation of the feeding mechanism.

Referring more particularly to the drawing the numeral 10 designates generally the pencil barrel, which may be of any desired size and configuration and constructed of any suitable material. The barrel is provided with a bore 11, having an enlarged portion 12, adjacent the end 13 of the barrel. Connected with the end 13 of the barrel is a tip 14, which is secured in position in any suitable manner and is provided with a reduced extremity 15, the free extremity 50 of the tip being preferably provided with a slot or kerf 16, extending through the end thereof to produce a spring action at the end of the tip. The bore in the tip is in

alinement with the bore of the barrel 10, so that the lead or crayon 17 may be fed from 55 the barrel and through the tip 15.

Arranged within the bore 11 of the barrel is a plunger 18, which is preferably provided adjacent its upper end with a collar or shoulder 19, against one end of which a 60 spring 20 rests, while the other end of the spring abuts the end 21 of the bore 11. The normal tendency of the spring 20 is to force the plunger 18 forwardly or in a direction lengthwise of the barrel to project the extremity of the lead or crayon through the end of the tip.

The plunger 18 is provided with a series of spaced shoulders 22, of any desired construction but are preferably shaped so as to 70 form ratchet teeth, which may extend for any desired distance lengthwise of the plunger 18.

Arranged within the enlarged portion 12 of the bore of the barrel is an escapement member 23, which may be of any desired configuration and is shaped to form pawls or teeth 24—25, and the escapement is pivotally mounted as at 26, preferably intermediate the pawls or teeth 24—25. The end 26' of the escapement beyond the pawl or tooth 24 is shaped to form a spring portion 27, while the extremity 28 of the end 29 is shaped to form a projecting portion adapted to stand within and pass through an opening 30 in the tip 14.

With this construction it will be manifest that as the natural tendency of the spring 20 is to feed or move the plunger 18 forwardly the lead or crayon 17 will be projected through the extremity of the tip 15, and therefore in order to control the extent of the feeding movement of the plunger it is only necessary to oscillate the escapement member 23 about its pivot 26, so that the 90 teeth or pawls 24—25 thereon will be brought alternately into and out of engagement with the shoulders or teeth 22 on the plunger 18. Any suitable means may be provided for oscillating the escapement 100 about its pivot 26, but the preferred manner of controlling this oscillating movement is by means of a cap 31, which encompasses the tip 15 and is provided with a tapering bore 32 adjacent its extremity. The upper 105 end 33 of the cap 31 is shaped to form an

enlarged opening 34, the wall of which opening is provided with screw threads 35, adapted to cooperate with screw threads 36 on the portion 37 of the tip 15, so that when 5 the cap 31 is screwed in one direction upon the portion 37 of the tip 15, the cap will be adjusted to cause the spring portion at the lower end of the tip 15 to clamp the lead or crayon 17, but when the cap 31 is adjusted in the opposite direction the cap will 10 move forwardly so that the spring portion at the end of the tip 15 will release the lead or crayon 17, so as to permit of a feeding movement under the influence of the 15 spring 20.

The upper extremity of the portion 33 of the cap 31 projects over the opening 30 in the barrel 10 and is provided with a cam shaped portion or recess 38, adapted to be 20 moved into and out of register with the opening 30 in the tip 15.

When the cap 31 is adjusted so that the cam shaped portion or recess 38 therein is in register with the opening 30, the spring 25 portion 27 of the escapement 23 by reason of its action upon the wall of the enlarged portion 12 of the bore in the barrel will cause the escapement to rock about its pivot 26 in a direction to move the pawl or tooth 30 25 away from the shoulders 22 on the plunger 18, and will move the pawl or tooth 24 into a position within the path of the advancing movement of one of the shoulders 22 to be engaged by the latter and thereby 35 arrest the movement of the plunger 18 as shown in Figure 2. This will be accomplished when the cap 31 is rotated in one direction. When the cap is rotated in the opposite direction so as to move the cam or 40 recessed portion 38 out of register with the opening 31, as shown in Figure 1, the adjacent portion of the wall of the cap will engage the extremity 28 of the portion 29 of the escapement 23 to rock the escapement 45 in the opposite direction about its pivot and against the stress of the spring portion 27 of the escapement and will thereby move the pawl or tooth 24 out of the path of movement of the shoulders 22, and will move the 50 pawl or tooth 25 into the path of movement of the shoulders to be engaged thereby and further arrest the movement of the plunger.

It will therefore be seen that by an oscillating movement of the cap 31 first in one 55 direction and then in the opposite direction the escapement 23 will be rocked about its pivot and an intermittent or step by step movement will be imparted to the plunger 18 through the medium of the spring 20.

As the cap 33 is moved in one direction to cause the cam or recessed portion 38 to move 60 into register with the opening 30 the cap will be moved in a direction to permit the spring extremity of the tip 15 to expand and 65 when the cap is moved in the opposite direc-

tion to move the portion 38 out of register with the opening 30 the extremity of the tip will be caused to clamp the lead or crayon.

If desired the upper portion of the barrel may be provided with another recess 39 for 70 the reception of additional leads or crayons 40, and a removable cap 41 carrying an eraser 42 may be detachably secured in any suitable manner upon the other end of the barrel.

While the preferred form of the invention has been herein shown and described it is to be understood that various changes may be made in the details of construction and in the combination and arrangement of the 80 several parts, within the scope of the claims without departing from the spirit of this invention.

What is claimed as new is:—

1. A pencil embodying a barrel, a tip 85 connected with the barrel, the extremity of the tip being shaped to form a spring portion, a spring actuated plunger within the barrel and operating normally to force the lead from the barrel and through the tip, 90 an adjustable cap co-operating with the tip for controlling the gripping action of the tip upon the lead, and means controlled by the adjustment of said cap for controlling the feeding action of the plunger upon the 95 lead.

2. A pencil embodying a barrel, a tip connected with the barrel, the said tip being shaped to form a gripping portion to grip the lead, a spring actuated plunger operating 100 to force the lead from the barrel and through the tip, a cap co-operating with the tip and adjustable in one direction to cause the tip to grip the lead and adjustable in another direction to cause the tip to release 105 the lead, and means whereby the adjustment of the cap in one direction will permit the said plunger to move one step and the adjustment of the cap in the opposite direction will permit the plunger to move an- 110 other step.

3. A pencil embodying a barrel, a tip connected with the barrel, the said tip being shaped to form a gripping portion to grip the lead, a spring actuated plunger operating 115 to force the lead from the barrel and through the tip, a cap co-operating with the tip and adjustable in one direction to cause the tip to grip the lead and adjustable in another direction to cause the tip to release 120 the lead, and means whereby the adjustment of the cap in one direction will permit the said plunger to move one step and the adjustment of the cap in the opposite direction will permit the plunger to move an- 125 other step, the said means embodying an escapement device.

4. A pencil embodying a barrel, means at the end of the barrel for gripping and releasing the lead, means within the barrel 130

for automatically feeding the lead forward when the latter is released by the gripping means, means for controlling the said gripping means, and means responsive in its 5 operation to the operation of the said controlling means for limiting the extent of feeding movement of the lead.

5. A pencil embodying a barrel, means at the end of the barrel for gripping and releasing the lead, means within the barrel for automatically feeding the lead forward when the latter is released by the gripping means, means for controlling the said gripping means, and means embodying escape- 10 mechanism entirely housed within the pencil and responsive in its operation to the operation of the said controlling means for limiting the extent of feeding movement of the lead.

20 6. A pencil embodying a barrel, means at the end of the barrel for gripping and releasing the lead, means within the barrel for automatically feeding the lead forward when the latter is released by the gripping 25 means, means for controlling the said gripping means, and mechanism embodying an escapement for limiting the extent of feeding movement of the lead, and a cam sur- face controlled by the third recited means 30 and operable upon the said escapement for controlling the operation of the latter.

7. A pencil embodying a barrel, means at the end of the barrel for gripping and releasing the lead, means operating auto- 35 matically to feed the lead, and means operating to control both the lead feeding and gripping means.

8. A pencil embodying a barrel, means at the end of the barrel for gripping and releasing the lead, means operating automatically to feed the lead, means for controlling the said gripping means, and means where- 40 by the said controlling means will cause a step by step movement to be imparted to 45 the lead feeding means.

9. A pencil embodying a barrel, means at the end of the barrel for restraining the lead,

a spring actuated plunger for feeding the lead, spaced shoulders on the plunger, a double pawl co-operating with the shoulders 50 for permitting a step by step feeding movement of the plunger, and means for controlling at will the operation of the pawl.

10. A pencil embodying a barrel, means at the end of the barrel for restraining the 55 lead, a spring actuated plunger for feeding the lead, spaced shoulders on the plunger, a double pawl co-operating with the shoulders for permitting a step by step feeding move- 60 ment of the plunger, and means for con- trolling at will the operation of the pawl, the last recited means also operating to control the said restraining means.

11. A pencil embodying a barrel, means at the end of the barrel for holding the lead 65 against movement with relation to the barrel, a spring actuated plunger for feeding the lead, spaced shoulders on the plunger, a spring controlled pawl co-operating with the said shoulders for limiting the extent of 70 feeding movement of the plunger, means for controlling the first recited means, and a cam surface connected with the second recited means and operable to control the action of the said pawl.

75 12. A pencil embodying a barrel, means at the end of the barrel for holding the lead against movement with relation to the barrel, a spring actuated plunger for feed- 80 ing the lead, spaced shoulders on the plun- ger, a spring controlled pawl co-operating with the said shoulders for limiting the ex- tent of feeding movement of the plunger, means for controlling the first recited means, and a cam surface connected with the 85 second recited means and operable to con- trol the action of the said pawl, the said feeding means and the controlling means therefor being all housed and concealed within the pencil.

90 In testimony whereof I have signed my name to this specification, on this 10th day of February, A. D. 1922.

RAYMOND T. BELL.
